UNITED STATES PATENT OFFICE.

WILLIAM C. KISNER, OF WATSON, WEST VIRGINIA.

TRAP NEST.

Application filed May 4, 1922. Serial No. 558,327.

To all whom it may concern:

Be it known that I, WILLIAM C. KISNER, a citizen of the United States of America, and resident of Watson, county of Marion, 5 and State of West Virginia, have invented certain new and useful Improvements in Trap Nests, of which the following is a specification.

This invention relates broadly to trap-nests for poultry, and it has for its primary object to provide an apparatus embodying a nest and mechanical means for trapping or confining a hen to said nest and for releasing such hen following the deposit of an egg in 15 the nest.

A further object is to provide an apparatus of the character mentioned in which the hen is trapped following entrance upon the nest, in which the hen is released automatically through the deposit of an egg, and in which the hen effects resetting of the parts of the mechanism in departing from the 20 nest.

A still further object is to provide in an apparatus of the character mentioned means whereby is effected registration of hens released from the nest in a manner affording identification of said hens.

With these and other objects in view the 30 invention resides in the features of construction, arrangement of parts and combinations of elements which will hereinafter be fully described, reference being had to the accompanying drawings, in which—

35 Figure 1 is a longitudinal section of the invention, showing the various parts occupying their initial operative positions;

Figure 2 is a horizontal sectional elevation of the same, the section being taken on line 2—2, Fig. 1;

Figure 3 is a similar section taken substantially on line 3—3, Fig. 1;

Figure 4 is a top plan view of the removable base with the egg-receiver mounted 45 in place thereon;

Figure 5 is a rear end elevation of the invention;

Figure 6 is a detail section taken substantially on line 6—6, Fig. 3;

50 Figure 7 is a side elevation of the tape carrying and advancing mechanism;

Figure 8 is an enlarged detail view in sectional elevation illustrating the entrance-door controlling means; and—

55 Figure 9 is a detail view showing a hole

of the character employed for the passage of the spirally ribbed portion of the door-supporting rods.

Referring to said drawings, 1 indicates the upright lower section of a cylindrical casing which is mounted upon a detachable base 2, said base having an upright annular flange 3 which is embraced by the lower end of said casing section. Located at a suitable elevation within said casing section 1 is a short, concentrically disposed sleeve 4, the same being carried by horizontally disposed supporting brackets 5 which are mounted upon the casing walls. Telescoped within and adapted for vertical movement with respect to said sleeve 4 is a tubular member 6 formed at the apex of a widely flared or conical vessel or nest 6 which normally occupies a position with its upper edge located adjacent to the walls of the casing section 1 near the upper end of the latter.

The upper end of the casing section 1 has a slightly reduced neck portion 1^a which is embraced by the lower end of an upper cylindrical casing section 7 which removably seats upon said section 1, forming a nest compartment. Provided in the front side of said casing section 7 is an entrance doorway 8 having associated therewith a pair of complementally related swinging doors 9 whereby access for hens through said doorway is controlled. Each of said doors has its outer edge fixed upon an upright rod 10 which is mounted for rotary movement to permit swinging to and from closing relation to 90 said doorway. The upper ends of said rods 10 are received by and are rotatable in holes 11 provided therefor in a laterally extending flange 12 formed on the top 13 of the upper casing section 7, and the lower end 95 portions of said rods are directed through the horizontal ledge 14 which, through the production of the neck 1^a, is formed on the casing section 1. The extreme lower ends of said rods rest upon an outwardly directed top flange 6^a formed upon the funnel shaped nest 6, as is best shown in Fig. 8 of the drawings. The portion of each of said rods which penetrates the ledge 14 has formed thereon a spiral thread or rib 15, and the 100 openings or holes 16 in said ledge conform substantially in size and shape to the cross section of the ribbed portions of the rods, so that when said rods are elevated or lowered rotary movement will be imparted thereto. 110

The arrangement of the ribs 15 and the holes 16 is such that when the nest 6 occupies its normal position, said doors will be maintained in open position, and when said nest is lowered, the doors are actuated to swing to doorway-closing position actuated by their weight combined with that of the rods.

Provided in the upper casing section 7 in a position diametrically opposite the entrance doorway 8 is an exit doorway 17 controlled by a pair of complementary doors 18 which are mounted upon rods 19. Said rods 19 substantially correspond with the rods 10, except that their lower ends are directed through the top flange 6^a of the nest 6 and have nuts 20 threaded thereon into seated relation to the upper face of said flange and have nuts 21 threaded thereon at a spaced distance from the under face of said flange, and the ribs 22 of said rods 19 have a reverse winding. Thus, when the nest 6 occupies its normal elevated position, the doors 18 are held closed; and when said nest is lowered throughout a predetermined distance, the rods 19 are drawn downward therewith for actuating said doors to swing to open position.

The exit doorway 17 opens from the casing 7 into the forward end of a chamber or compartment 23 within a substantially rectangular casing 24 which has its rear, or outer, end controlled by complementary swinging doors 25, these doors being preferably of wire-screen type and having their vertical supporting rods 25^a mounted at their upper ends in the top of said casing 24 and at their lower ends in a horizontal bar 26 carried by the front end of the bottom of said casing. The lower end portions of said rods have spiral threads or ribs 27 and operate through holes 28 provided for in said bar 26, the arrangement being such that the weight of the doors 25 maintains said rods lowered to positions in which said doors occupy closed positions. Said doors 25 do not meet in their said closed positions, but are separated to provide an intermediate space of such width that the head of a hen may be thrust outward between the doors preliminary to forcing the same open to permit of her departure, following which said doors automatically return to closed position.

Carried exteriorly upon opposite sides of the conical portion of the nest 6 are depending nest-supporting lugs 29 which are mounted upon the parallel front end portions 30^a of companion frame members designated generally by the reference character 30. Said frame members, which occupy substantially horizontal positions, converge from said end portions 30^a into meeting relation, as shown at 30^b, and the meeting portion 30^b is extended outward

through a vertical slot 31 provided therefor in the rear side of the lower casing section 1. Further, said meeting portion 30^b is pivotally mounted within said casing section 1 upon a pivot-pin 32 carried by supporting brackets 33 mounted on said casing at opposite sides of said slot. Outside said casing section said frame members first diverge and then extend rearward forming substantially parallel rear end portions 30^c. Supported by said end portions 30^c are certain mechanisms which will hereinafter be described and which serve as a counterbalance whereby the forward end of said frame is normally held elevated for supporting the nest 6 in its normal elevated position.

As hereinbefore stated, the entrance doors 9 are normally held in open position, being actuated to assume said position by the upward pressure or force exerted upon the lower ends of the door-carrying rods 10 by the elevated nest 6. However, when a hen enters between said open doors 9 and steps upon said nest 6, the weight so imposed upon the nest overcomes that of the mechanism borne by the outer end of the frame 30, and the said frame consequently swings upon its pivot 32, allowing lowering of said nest throughout the short distance necessary to allow the entrance doors 9 to close, which distance, however, is insufficient to initiate opening of the exit doors 18, due to the fact that the nuts 21 borne by the lower ends of the rods 19 are not engaged until the limit of said lowering movement of the nest has been reached.

A horizontal pin 35 has its inner end normally projecting inward through a hole 36 provided therefor in the sleeve 4 and forms a stop upon which the tubular member 6 of the nest seats when the latter assumes the lowered position above referred to. Said pin is supported for longitudinal movement by the sleeve-embracing portion 5^a of the adjacent bracket 5 and by a cross-web 37 connecting the substantially parallel members of a bracket 38 which is stationarily supported in a suitable manner, as by said bracket 5. A spiral pin-encircling spring 39 having its outer end resting against said web 37 and its opposite end against a cross-pin 40 carried by said pin 35 tends to maintain the latter in the inwardly thrust position indicated. A flexible cord 41 has one end attached to the outer end of said pin 35, thence is passed over a small pulley 42 carried by the outer end of said bracket 38, and has its opposite end attached to the upper end of one of the substantially upright supporting arms 43 of a frame 44 in which is mounted a fabric or netting 45 of wire or other suitable material which underlies the sleeve 4 at a suitable distance from the latter. Said arms 43 are pivotally mounted on said bracket 130

38 and normally support said netting 45 in a substantially horizontal position.

When an egg is deposited by the hen on the nest, it rolls downward to the tubular member 6 and thence drops through the latter and the sleeve 4 to the netting 45. The weight of the egg upon said netting acts to effect swinging of the latter with its frame 44 to an inclined position in which 10 the egg is permitted to roll rearward therefrom to a stationarily mounted inclined chute 46 by which said egg is guided to a point whence it may drop to one of a plurality of pockets 47 provided for the reception of eggs in an egg-receiver which will hereinafter be described.

It will be manifest that the swinging movement of the netting frame 44 resulting from the deposit of the egg on the netting 20 will cause the upper end of the arm 43 to which the cord 41 is attached, as aforesaid, to swing forward, thus, through the intermediary of said cord and the pulley 42, drawing the pin 35 outward against the 25 tension of its spring 39. This movement of the pin results in its point being withdrawn from supporting relation to the nest, allowing the latter to drop to the limit of the downward movement thereof permitted by 30 the sleeve 4; and, in said movement the doors 18 are actuated to open for releasing the hen from the nest, a downward drawing force being then exerted upon the rods 19 by the descending nest.

35 Having entered the compartment 23 through the doorway 17, the hen is obliged in traversing said compartment to reach the doors 25 to step upon an ink-impregnated pad 48 mounted upon the bottom of the casing 24, and then upon a tape 49 of paper or other suitable material which is disposed in covering relation to a slightly elevated platform 50 located within said compartment adjacent to said doors 25. It is designed that 40 each hen having access to the nest shall have fastened to one of its feet a marking device of the general character disclosed in a companion application filed May 4, 1922, Serial No. 558,828, said device comprising a foot-carried 45 imprinting character which serves to distinguish each hen from the others. The character becomes inked through direct contact with the inking pad 48 when the hen steps on the latter and an ink impression or transfer 50 is then made upon the tape 49 as she crosses the platform 50. The hen is thus reliably credited with the egg which has been deposited in the egg-receiver as aforesaid.

The platform 50 consists of a plate disposed 55 transversely of the outer end of the compartment 23 and having its opposite ends mounted upon upright supports 51 which are vertically movable through openings 52 provided therefor in the bottom of the casing 59. Said supports have their lower ends rig-

idly mounted upon the parallel end portions 30° of the pivotally mounted frame 30. Consequently, said platform occupies a position elevated above the bottom of said casing 24 when the nest occupies its extreme lowered 70 position assumed prior to departure of the hen therefrom. When the hen mounts said elevated platform, her added weight suffices to depress said platform and through it, the rear end of the frame 30, whereby the nest 75 is returned to its normal elevated position; and, as said nest assumes said position, it actuates the exit doors 18 to close and the entrance doors 9 to open, thus automatically resetting the apparatus, or preparing it for 80 the next hen.

The tape 49 is provided in the form of a roll 53 which is carried by a spindle 54 journaled in brackets 55 depending from the under side of the casing 24. The tape leads 85 from said rolls to and under a suitable roller, as 56, journaled in bars 57 which are suspended by hangers 58 from said casing, thence extends upward through a slot 59 in the bottom of said casing to and over rollers 90 34 located on opposite sides of the top of the platform 50, and thence downward through a second slot 60 to and between rollers 61 and 62 by which traction is applied for advancing said tape. Said rollers 61 and 62 95 are journaled in the supporting bars 57, the larger roller 61 carrying upon an end thereof a pinion 63 in mesh with a gear 64 which is also journaled upon the adjacent end of a pin or shaft 65 carried by the supporting 100 bars 57. An arm 66 having an end pivoted at 67 upon the rear end of the adjacent frame member 30° carries a spring pressed dog 68 in engagement with the teeth of said gear 64. Said arm is also pivoted intermediate its ends upon the adjacent end of the shaft 65. Thus, when the nest 6 is initially depressed by a hen entering thereon, whereby is effected upward movement of the outer ends 30° of the frame members, as aforesaid 105 the arm 66 is thereby rocked upon said shaft 65 carrying said dog 68 downward and imparting a definite rotary movement to said gear 64 whereby the roller 61 is rotated forward throughout a distance which suffices to 110 advance the tape 49 for removing from the platform 50 the length thereof which has received the ink imprint identifying the departing hen, and for presenting a new length of said tape on the platform for receiving 115 the identifying print of the next hen.

The egg receiver hereinbefore referred to comprises a circular tray 69 which rests upon a plurality of rollers 70 journaled in lugs 71 carried by the removable bottom or base 2 120 of the lower cylindrical casing section 1. Said tray has removably mounted upon its upper face a circular pad 72, preferably formed of heavy felt paper or like cushioning material, pressed into a shape providing 125 130

a plurality of pockets 47 adapted for the individual reception of eggs as the latter are delivered from the chute 46.

Pivoted upon a stationary portion of the supporting frame 5, as upon a bracket 73, is the angle portion of a bell-crank lever 74. One arm of said lever extends laterally and is pivotally attached to a lug 75 carried on the under side of the nest 6, while the opposite arm extends downward and has formed upon its lower end a yoke 76 which loosely embraces a laterally disposed crank arm 77 formed upon a vertical pin or spindle 78 which extends through a central opening 79 in the tray 69 and has its lower end seated as a pivot in a central socket 80 provided therefor in the base 2. A ratchet wheel 81 is carried by said spindle 78 at a suitable point, and disposed in operative relation to said ratchet wheel is a spring-pressed pawl 82 which is pivotally mounted upon said tray. When, in the automatic resetting of the apparatus, as hereinbefore described, the nest 6 is actuated to rise to its normal elevated position, it acts to swing the bell-crank-lever 74 on its pivotal mounting in such manner that a slight forward swinging movement is imparted to the crank arm 77 for producing a partial rotation of the spindle 78. A corresponding partial rotation is communicated through the ratchet wheel 81 and the pawl 82 to the tray 69 whereby the latter is advanced to present the next succeeding unoccupied pocket 47 of the egg-receiving pad 72 in position for receiving the next egg delivered through the chute 46.

It will be manifest that the various eggs contained in a series in the pockets 47 may be readily identified as the product of certain hens through the identifying numbers which appear in certain order or series, upon successive paid-out lengths of the tape 49.

The doors 18 preferably have associated therewith means whereby the forcible opening thereof by a hen which has not deposited an egg in the nest may be positively prevented, it being intended that if such hen is released at all, it must be by way of the entrance doors 9 which may be swung outward by outwardly directed force applied thereto. The means herein disclosed comprises a latch 83 pivoted upon a suitable support, as 84, in an opening 85 provided in the top of the casing 24. Said latch normally stands with one leg 83^a in a position overhanging the upper edges of the doors 18. A forwardly extending leg 83^b directly underlies the end portion of a horizontally disposed spring-wire member 86 which is rigidly supported at its opposite end, as by a rivet 87. A rod 88 attached to said wire has its lower end directed through the flange 6^b of the nest 6 and has a nut 89 located on its lower end at a spaced distance from said

flange when the nest occupies its elevated position. Thus, the initial downward movement of the nest is permitted without tension being placed on the rod 88. When, however, the nest is permitted to drop following the deposit of an egg, as aforesaid, tension is applied to said rod whereby the wire 86 is sprung downward for tipping the latch 83 to a position in which it is withdrawn from holding relation to said doors.

Access to the interior of the casing 1, as for the removal of eggs from the egg receiver, or for adjustment or repair of the enclosed mechanism, is had through an opening 90 provided in the side of said casing. A suitable door, as 91, is normally disposed in closing relation to said opening, said door as herein shown being mounted at one side upon a pivot-pin 92 carried by the casing, and having a lug 93 at its opposite side receivable behind a keeper 94.

What is claimed is—

1. A trapnest comprising a nest compartment, horizontally swinging entrance and exit doors in the walls of said compartment, a vertically shiftable nest forming the bottom of said compartment, and means controlled by shifting movements of said nest whereby said doors are actuated to open and close in a predetermined order.

2. A trapnest comprising a nest compartment, entrance and exit doors in the walls of said compartment, means associated with each door normally tending to swing the latter from open to closed position, a vertically shiftable nest forming the bottom of said compartment, means normally supporting said nest in an elevated position in which the entrance doors are held open by said nest, said nest being adapted to be depressed by the weight of a hen entering thereon to a point permitting said entrance doors to close, means actuated by deposit of an egg in said nest to permit further depression of said nest to a point wherein the latter actuates the exit doors to open, and means actuated by the hen departing through said exit doors whereby said nest-supporting means are caused to elevate said nest to a point wherein the entrance doors are actuated to open and the exit doors are permitted to close.

3. A trapnest comprising a nest compartment, entrance doors in the wall of said compartment, a vertically shiftable nest forming the bottom of said compartment, a second compartment adjoining said nest compartment, exit doors controlling communication between said compartments, each of said doors having associated therewith automatic closing means, said nest being adapted in its elevated position to render the closing means for the entrance doors inoperative, said nest being depressible under the weight of a hen to a point permitting said entrance-

- door-closing means to operate, means actuated by deposit of an egg in said nest whereby further depression of said nest occurs under the weight of said hen, said nest 5 having connection with said exit doors whereby the latter are actuated by such further depression of the former to assume open position, and means actuated by a hen traversing said second compartment whereby said nest is reset in elevated position, effecting opening of the entrance doors and allowing the exit doors to close.
4. A trapnest comprising a nest compartment, a vertically shiftable nest forming the bottom of said compartment, means normally supporting said nest in elevated position, entrance doors in a wall of said compartment and arranged to be held open when the nest occupies its elevated position, means 10 acting to close said doors when said nest is depressed, said nest being compressible under the weight of a hen, means limiting the extent of initial depression of said nest, a second compartment adjoining said nest compartment and arranged to be held open when the nest occupies its elevated position, means 15 acting to close said doors when said nest is depressed, said nest being compressible under the weight of a hen, means limiting the extent of initial depression of said nest, a second compartment adjoining said nest compartment, normally closed exit doors controlling communication between said compartments, means actuated by deposit of an egg in said nest whereby said movement limiting means is caused to permit further depression 20 of the nest under the weight of the hen, means whereby said further depression of the nest actuates said exit doors to open, means actuated by a hen traversing the second compartment whereby the nest-supporting means are caused to return the nest to its elevated position, and means whereby such elevation of the nest effects actuation of the entrance doors to open position and the exit doors to closed position.
- 40 5. A trapnest comprising a nest compartment, a vertically shiftable nest forming the bottom of said compartment, means normally supporting said nest in elevated position, entrance doors in a wall of said compartment and arranged to be held open when the nest occupies its elevated position, means acting to close said doors when said nest is depressed, said nest being compressible under the weight of a hen, spring-pressed means 45 limiting the extent of initial depression of said nest, a second compartment adjoining said nest compartment, normally closed exit doors controlling communication between said compartments, means actuated by deposit of an egg in said nest whereby said movement limiting means is shifted against the tension of its spring to permit further depression of the nest under the weight of the hen, means whereby such further depression of the nest actuates said exit doors 50 to open, means actuated by a hen traversing the second compartment whereby the nest-supporting means are caused to return the nest to its elevated position, means whereby such elevation of the nest effects actuation 55 of the entrance doors to open position and the exit doors to closed position, an inkling pad located within said second compartment,
- such elevation of the nest effects actuation 65 of the entrance doors to open position and the exit doors to closed position, and a pocketed receiver for deposited eggs.
6. A trapnest comprising a nest compartment, a vertically shiftable nest forming the bottom of said compartment, means normally supporting said nest in elevated position, entrance doors in a wall of said compartment and arranged to be held open when the nest occupies its elevated position, means 70 acting to close said doors when said nest is depressed, said nest being compressible under the weight of a hen, means limiting the extent of initial depression of said nest, a second compartment adjoining said nest 75 compartment, normally closed exit doors controlling communication between said compartments, means actuated by deposit of an egg in said nest whereby said movement limiting means is caused to permit further depression of the nest under the weight of the hen, means whereby such further depression of the nest actuates said exit doors to open, means actuated by a hen traversing the second compartment whereby the nest-supporting means are caused to return the nest to its elevated position, and means whereby such elevation of the nest effects actuation of the entrance doors to open position and the exit doors to closed position, means 80 including a shiftable tape located within said second compartment whereby imprints are recorded by hens equipped with foot-carried identification markers as they traverse said compartment.
7. A trapnest comprising a nest compartment, a vertically shiftable nest forming the bottom of said compartment, means normally supporting said nest in elevated position, entrance doors in a wall of said compartment and arranged to be held open when the nest occupies its elevated position, means acting to close said doors when said nest is depressed, said nest being compressible under the weight of a hen, means limiting the extent of initial depression of said nest, a second compartment adjoining said nest 95 compartment, normally closed exit doors controlling communication between said compartments, means actuated by deposit of an egg in said nest whereby said movement limiting means is caused to permit further depression of the nest under the weight of the hen, means whereby such further depression of the nest actuates said exit doors to open, means actuated by a hen traversing the second compartment whereby the nest-supporting means are caused to return the nest to its elevated position, and means whereby such elevation of the nest effects actuation of the entrance doors to open position and the exit doors to closed position, means 100 including a shiftable tape located within said second compartment whereby imprints are recorded by hens equipped with foot-carried identification markers as they traverse said compartment.
- 105
- 110
- 115
- 120
- 125

a shiftable tape located rearward of said pad, and means for automatically advancing said tape.

8. A trapnest comprising a nest compartment, a vertically shiftable nest forming the bottom of said compartment, means normally supporting said nest in elevated position, entrance doors in a wall of said compartment and arranged to be held open when the nest occupies its elevated position, means acting to close said doors when said nest is depressed, said nest being depressible under the weight of a hen, means limiting the extent of initial depression of said nest, a second compartment adjoining said nest compartment, normally closed exit doors controlling communication between said compartments, means actuated by deposit of an egg in said nest whereby said movement limiting means is caused to permit further depression of the nest under the weight of the hen, means whereby such further depression of the nest actuates said exit doors to open, means actuated by a hen traversing the second compartment whereby the nest-supporting means are caused to return the nest to its elevated position, means whereby such elevation of the nest effects actuation of the entrance doors to open position and the exit doors to closed position, an inking pad located within said second compartment a shiftable tape located rearward of said pad, and means operated by nest-elevating actuation of the nest-supporting means whereby said tape is advanced.

9. A trapnest comprising a vertically shiftable nest, means normally supporting said nest in elevated position, and means controlling ingress to and egress from said nest, said controlling means being shiftable with movements of said nest, said nest being initially depressible under the weight of a hen, being further depressible under said weight following deposit of an egg, and being returnable to its elevated position by a hen following departure of the latter therefrom.

10. A trapnest comprising a vertically shiftable nest, means normally supporting said nest in elevated position, means controlling ingress to and egress from said nest, said controlling means being shiftable with movements of said nest, said supporting means having a pivoted arrangement and being adapted to permit initial depression of said nest under the weight of a hen, to permit further depression of said nest following the deposit of an egg, and being adapted to be actuated to return said nest to its elevated position by the weight of the hen imposed thereon following departure of the latter from the nest.

In testimony whereof, I affix my signature in presence of two subscribing witnesses.

WILLIAM C. KISNER.
